UNITED STATES PATENT OFFICE.

FRANK J. LUICK, OF CLEVELAND, OHIO.

CURRENT MOTOR.

Application filed October 6, 1921. Serial No. 505,805.

To all whom it may concern:

Be it known that I, FRANK J. LUICK, a citizen of the United States, residing at Cleveland, in the county of Cuyahoga, State of Ohio, have invented a new and useful Current Motor; and I do hereby declare the following to be a full, clear, and exact description of the invention, such as will enable others skilled in the art to which it applies to make and use the same.

The invention relates to current motors and has for its object to provide a device of this character adapted to be disposed on the bottom of a stream and comprising a wheel disposed within the casing, said casing being provided with intake and discharge pipes in alignment with each other and tangentially disposed in relation to the wheel.

A further object is to provide the wheel with T-shaped brackets, between the ears of which feathering water engaging blades are pivoted, said brackets also forming means for limiting the pivotal movement of the blade on the driven side of the wheel.

With the above and other objects in view the invention resides in the combination and arrangement of parts as hereinafter set forth, shown in the drawings, described and claimed, it being understood that changes in the precise embodiment of the invention may be made within the scope of what is claimed without departing from the spirit of the invention.

In the drawings:—

Figure 1 is a top plan view of the water wheel, showing the cover removed from the casing.

Figure 2 is a transverse sectional view through the turbine wheel and casing.

Figure 3 is a detail perspective view of one of the pivoted blades, its T-shaped bracket and a portion of the wheel.

Referring to the drawing, the numeral 1 designates a round turbine wheel casing, which casing is adapted to be disposed on the bottom 2 of a stream 3 with its tangentially disposed intake end 4 disposed upstream, and its tangentially disposed discharge portion 5 disposed downstream. The intake and discharge portions 4 and 5 are preferably in alignment with each other as shown in Figure 1 and tangentially disposed in relation to the casing 1. The intake pipe 4 is preferably flared as shown so that the

water will pass through the portion 6 of the chamber 7 of the casing 1 and engage the blades 8, which blades are carried by outwardly extending T-shaped brackets 9 radially disposed on the outer periphery of a wheel 10. Wheel 10 is mounted on a vertically disposed shaft 11 which shaft extends above the cover or top of the wheel pit, and is provided with a pulley 12, or bevel-gear wheels to which pulley or gear wheels any kind of machinery it is desired to operate may be belted (or geared) by means of a belt or gear wheels 13. The wheel 10 comprises a horizontally disposed flange 14 and the annular rim 15, which rim is substantially the same width as the depth of the chamber 7, which serves as the fourth side of a tight flume, and which serves as the fourth side of a closed flume together with the top 16 of the casing and the bottom 17 of said casing. The wheel 10 as a whole is mounted on antifrictional bearings 18 thereby reducing the friction to a minimum during the rotation of the wheel. The brackets 9 are T-shaped as shown in Figure 3 and have their vertically disposed arms 19 terminating in vertically aligned ears 20, between which ears the inner ends 21 of the blade 8 are pivoted. It will be seen that as the water enters the intake member 4 that it will engage the blades 8 and rotate the turbine wheel in the direction of the arrow *a*. As the wheel rotates in the direction of the arrow *a*, the blades will feather as shown in Figure 1 thereby preventing back pressure or churning of water which is in the portion 7^a of the chamber 7. The outer wall 1^a of the casing 1 is positioned in relation to the pivotal points of the blades 8 and the free ends of the blades 8^a whereby as each blade moves to operative position, said wall 1^a would prevent the blade from being forced to the wrong side of the bracket 9 if the current should turn the blade outwardly instead of inwardly.

The top 16 of the casing 1 may be provided with a hinged member 22 whereby access may be had to the interior of the casing 1 for repair and cleaning purposes.

From the above it will be seen that a turbine is provided, wherein the blades will feather and be prevented from becoming reversed in position by the wall of the casing, thereby obviating the use of stops on the blades or brackets 9, which is now the com-

100

105

110

mon practice. It will also be seen that a turbine is provided which may be disposed on the bottom of a stream and power developed thereby utilized for driving various kinds of machinery or an electric generator if so desired.

The invention having been set forth what is claimed as new and useful is:—

1. A turbine wheel comprising a horizontally disposed casing having a horizontally disposed turbine wheel therein, intake and discharge pipe carried by said casing, said intake and discharge pipes being in alignment with each other and tangentially disposed on the casing, radially disposed T-shaped brackets carried by the wheel, said T-shaped brackets having their arms vertically disposed and terminating in horizontally disposed ears, feathering blades pivoted between said ears, the walls of said casing being so positioned in relation to the pivotal points of the feathering blades that the free ends of the blades will be prevented from becoming reversed during the rotation of the turbine wheel, the brackets also

forming limiting means for limiting the inward movement of the blades.

2. A submerged current motor, said motor comprising a horizontally disposed casing having a chamber therein, a turbine wheel disposed in said casing, T-shaped brackets, blades carried by said turbine wheel and pivoted to T-shaped brackets, a shaft extending upwardly from said turbine through the casing and adapted to terminate above the surface of a stream and forming means whereby power may be transmitted to machinery to be driven, and intake and discharge pipes in connection with said casing, said intake and discharge pipes being in alignment with each other and tangentially disposed in relation to the casing and turbine.

In testimony whereof I have signed my name to this specification in the presence of two subscribing witnesses.

FRANK J. LUICK.
